[57] CLAIM

the ornamental design for a cross country ski pole wrist strap, as shown and described.

DESCRIPTION

FIG. 1 is a front perspective view of a cross-country ski pole wrist showing my new design;

FIG. 2 is a front perspective view of a second embodiment of the ski pole wrist with option overhand attachment in pole;

FIG. 3 is a left side view of FIG. 1;

FIG. 4 is a rights side view of FIG. 1;

FIG. 5 is a top view of FIG. 1;

FIG. 6 is a side view of FIG. 1 showing the wrist strap in disconnected from a pole with the hook and loop fastener disengaged and removed from the buckle in an unfolded position;

FIG. 7 is a front view of the optional strap of FIG. 2 disconnected from the strap; and,

FIG. 8 is the opposite side view of FIG. 6.

The broken lines in FIGS. 1 through 4 are for illustrative purposes only and form no part of the claimed design. The smaller broken lines in the strap indicate stitching.

FIG. 1.

FIG. 2.
